(57) **CLAIM**

I claim the ornamental design for a table, as shown and described.

DESCRIPTION

FIG. 1 is a rear perspective view of my design for a table. FIG. 2 is a front perspective view of the design of FIG. 1.

FIG. 3 is a top view of the design of FIG. 1.

FIG. 4 is a bottom view of the design of FIG. 1.

FIG. 5 is a right side elevational view of the design of FIG. 1.

FIG. 6 is a front elevational view of the design of FIG. 1, the rear elevational view being substantially identical except for the lower base being rounded as shown in FIG. 1; and, FIG. 7 is a left side elevational view of the design of FIG. 1.
